EDGAR S. STODDARD, OF BERWYN, ILLINOIS, ASSIGNOR TO THE CONOVER COMPANY, OF CHICAGO, ILLINOIS, A CORPORATION OF ILLINOIS

DISHWASHING MACHINE

Application filed May 24, 1928. Serial No. 280,128.

This application relates to improved hinge and lid support construction for dishwashing machines, which hinge and lid construction is especially adapted for utilization in portable dishwashing machines of large diameter.

In dishwashing machines it is frequently desirable to place the cover in inverted horizontal position and then to utilize such cover as a holder for the racks while they are being loaded or unloaded. In order to enable the inverted cover to perform this function it is necessary to suitably support it so that an unbalanced load in the racks set upon it will not tend to spring the hinge.

The object of this invention is to provide an improved hinge and lid support construction which is adapted to be utilized in connection with dishwashing machines.

The drawings illustrate one embodiment of the invention.

Figure 1 represents a vertical sectional view of the dishwashing machine with the cover closed and with the racks in position;

Figure 2 represents a front view of the hinge and lid support construction when the cover has been removed from its closed position by an angle of 90°;

Figure 3 represents a side sectional view of the hinge and lid support construction when the lid is in inverted horizontal position; and

Figure 4 represents a sectional top view upon the line 4—4 of Figure 2.

In Figure 1 the tank 11 of the washing machine is provided with a conical or centrally drained bottom 12 and a cover 13. The side of the tank 11 is provided with two strengthening grooves 14. From the upper

one of the strengthening grooves is suspended the upper dish rack 15 which is especially adapted to hold deep vessels such as glasses, cups, etc. In the washing chamber the lower rack 16 is adapted to be supported directly upon the dished bottom 12 of the tank 11.

Attached to the side of the tank 11 and supporting it are three symmetrically positioned legs 20, the lower ends of which are provided with the rollers 21. In the lowest central portion of the washing chamber substantially below the dish racks, is positioned an impeller 22, which is driven by the inferiorly positioned motor 23. The motor 23 is supported by the spider 24, the ends of the arms of which are attached to the legs 20. The machine is provided with an adjustable swinging conduit 25 which is adapted to receive liquids to be admitted to the washing chamber or which is adapted to discharge liquids which have been utilized in the washing chamber of the machine. The end of the conduit 25 is provided with an adjustable funnel 26 which can be turned upwardly to receive liquids or downwardly to discharge liquids.

At the lowest part of the washing chamber of the machine is positioned a well chamber 30 which is divided into two compartments by the plate 31. In the lowest compartment is a centrifugal device 32 which is attached to the lower part of the shell of the impeller 22 and which is also driven by the motor 23.

One side of the lid 13 is provided with a handle 40 which is adapted to fit the hand. To the side of the cover 13 adjacent to the rear leg is attached the hinge and lid support construction which will now be described (see Figures 1, 2 and 3). To the rear of the lid is attached a plate 41 which is provided with two rolled portions 42 forming bearings 43 for one end of the guide rods 43. The other ends of these guide rods 43 are adapted to fit into bearings 44 in the T-shaped lid support rod. The T-shaped lid support rod comprises a horizontal member 46, the upper side of which is adapted to contact with the lid when in inverted horizontal position, as shown in Figure 3. The horizontal rod 46 is attached to two angular rods 47 which coalesce and join with the vertical rod 48.

The vertical rod 48 is held in a yoke 49 by means of the bolt 50. The yoke 49 is attached to the rear leg and to a bracket 52 by means of the bolt 51.

5 The yoke 49 is constructed of material of sufficient strength to prevent its being deformed by the load it is subjected to. The guide legs 73 are designed to closely fit the outside of the leg 20 to prevent the rotation 10 of the bracket 49 and to assist in rigidly holding the support rod.

The other side of the plate 41 than that which contains the bearings 42 is also provided with a series of bearings 60 which interfit into and with a series of upwardly projecting bearings 62 which are part of the member or plate 61. Through these interfitting bearings 60 and 62 (see Figure 2) is passed a bearing rod 63 on which the lid is 20 hinged. The plate 61 (see Figure 4) which constitutes the lower section of the cover hinge is constructed to fit the contour of the tank. The radial pads 71 are provided at the radial bolt holes 75 to assist in tightening 25 the hinge plate 61 without distorting the tank 11 and brackets 67. The outer face of the hinge is provided with tapered washers 72 to support the heads of the radial screws or bolts 66 upon the outer flat surface of the 30 plate 61. A central tail piece 64 is provided to rigidly fasten the rear leg 20 to the plate 61. The plate 61 is attached to the rear leg by means of the bolt 65 and is attached to the body of the tank by means of the bolts 35 66 and the brackets 67.

If desired, the lid support construction shown may be modified so that the angular cross pieces 47 will be combined with the horizontal portion 46 to form a single combined T-portion. In some instances, to prevent the top of the horizontal portion 46 from marking the lid it may be desirable to place a rubber tube or other flexible material around the horizontal member 46.

45 The guide rods 43 serve to locate the straight hinged support rod on the surface of the horizontally opened cover at a sufficient distance from the tank to give efficient support. They also fold the hinged support 50 rod close to the side of the tank, out of the way, when the cover is in closed position. The guide rods 43 and the support rod 46 are so adjusted that there will be sufficient space between the guide rods and support and the 55 machine to prevent the operator's fingers from being squeezed or pinched during opening or closing of the cover.

What is claimed is:

1. In a hinge and lid support construction 60 for washing machines, a hinged lid and a vertical bar, the lower end of which is pivotally attached to the rear leg of the machine at a point substantially below the top of the machine and the upper end of which is provided with a T-shaped portion which is

adapted to support the lid when in inverted horizontal position, which T-shaped portion is connected to the lid by swinging guide rods.

2. A washing machine comprising a tank, a cover for said tank, a T-shaped support rod for the cover when in inverted horizontal position, the cover being provided at the hinge side with a plate attached to the cover, one side of the plate being rolled to form a bearing for guide rods attached to the upper 70 part of the T-shaped support rod and another side being rolled to form a bearing for the hinge rod.

3. A tank for a washing machine with a cover fixedly hinged to the top of the tank, a substantially straight rod pivotally attached at the lower end to the tank at a point substantially below the top of the tank, and terminating at the top end in an enlarged contact area, said enlarged contact area being adapted to contact with the inverted top of cover when cover is open and in inverted horizontal position at a substantial distance 80 from the hinge.

4. A tank for a washing machine with a hinged cover, a substantially straight rod, pivotally attached at the lower end to the tank and terminating at the upper end in an enlarged contact area, with guides to automatically position the said enlarged area in 90 contact with the horizontally opened tank cover to provide maximum supporting effect.

5. A tank for a washing machine with a cover fixedly hinged to the top of the tank, a substantially straight rod pivotally attached at the lower end to the tank and terminating at the upper end in an enlarged contact area, whose greatest dimension is parallel to the hinge rod upon which the cover rotates, said enlarged contact area being adapted to contact with the inverted top of cover when cover is open and in inverted horizontal position at a substantial distance from the hinge.

6. A tank for a washing machine with a hinged cover, a substantially straight rod, pivotally attached at the lower end to the tank frame work and terminating at the upper end in an enlarged contact area, whose greatest dimension is parallel to the rod upon which the cover hinge rotates, said contact area being automatically positioned beneath horizontally opened cover by means of guide rods attached both to said cover and to said support rod.

7. A tank for a washing machine with a hinged cover, and a substantially straight rod, pivotally attached at the lower end to the rear leg supporting the tank by means of a yoke which is attached to said leg and which is further provided with short legs which 105 grasp said leg.

8. A tank for a washing machine provided with a hinged cover, said hinge structure comprising two interfitting members which are adapted to form a straight bearing for the 110

- hinge rod, one member being rigidly attached to the cover and the other member being formed to fit the contour of the tank, said last mentioned member being provided with radially positioned pads containing radial bolt holes for rigidly attaching said member to brackets attached to the side of the tank.
9. A tank for a washing machine provided with a hinged cover, said hinge structure comprising two interfitting members which are adapted to form a straight bearing for the hinge rod, one member being rigidly attached to the cover and the other member being formed to fit the contour of the tank, said last mentioned member being provided with radially positioned pads containing radial bolt holes for rigidly attaching said member to brackets attached to the side of the tank and tapered washers adapted to support the heads of the radial bolts rigidly upon the flat outer surface of the lower hinge member.
10. In a hinge and lid support construction for vertical tank, a hinged lid and a vertical bar, the lower end of which is movably attached to the rear leg of the machine at a point substantially below the top of the machine and the upper end of which is provided with an enlarged portion which is adapted to support the lid when in inverted horizontal position, which enlarged portion is connected to the lid by swinging guide rods.
11. A tank, provided with a cover, a swinging support rod for the cover when in inverted horizontal position, swinging guide rods attached to the top of the support rod and the cover, the cover being provided at the hinge side with a plate attached to the cover, the inner side of the plate being rolled to form a bearing for guide rods and the outer side being rolled to form a bearing for the hinge rod.
12. A vertical tank provided with a hinged cover, straight rods, fixedly and pivotally attached to the tank at a point substantially below the top of the tank and to the lid a substantial distance from the hinge at one end respectively and pivotally attached to each other at their other ends, the second mentioned end of one of said rods being adapted to form a support for the lid when in opened position.
13. A vertical tank provided with a hinged cover, a swinging vertical rod pivotally attached at its lower end to the tank structure a substantial distance below the position of the hinge and adapted to support the lid when in open position with its upper end, and means to swing the vertical rod away from the tank when the cover is lifted so that it will support the inverted cover a substantial distance from the position of the hinge and to swing the vertical rod toward the tank when the cover is closed so that it will be positioned closely adjacent thereto.
14. In combination with a vertical tank open at its top, a hinged cover, and a substantially straight rod pivotally attached to the side of the tank a substantial distance below the opening and provided at its upper end with an inverted triangular portion the apex of which joins with the straight rod and the base of which is adapted to support the cover when in inverted position.
- In testimony whereof I have hereunto subscribed my name.
- EDGAR S. STODDARD.
